UNITED STATES PATENT OFFICE.

ERICK G. ANDERSON, OF SPOKANE, WASHINGTON.

WATER-MOTOR.

1,275,355.

Specification of Letters Patent. Patented Aug. 13, 1918.

Application filed August 21, 1916. Serial No. 116,114.

To all whom it may concern:

Be it known that I, ERICK G. ANDERSON, a citizen of the United States, residing at Spokane, in the county of Spokane and State 5 of Washington, have invented certain new and useful Improvements in Water-Motors, of which the following is a specification.

This invention relates to water motors, and more particularly to a motor adapted to be 10 operated by the current of a stream or river.

One of the main objects of the invention is to produce a motor of the character stated of simple construction and high efficiency. A further object is to provide a motor in 15 which the operating means may be adjusted vertically so as to be moved into or out of operative position, as desired. Further objects will appear from the detailed description.

20 In the drawings:—

Figure 1 is a sectional view taken on a plane flush with the top of the float, looking down,

Fig. 2 is a section on line 2—2 of Fig. 1,

25 Fig. 3 is a section on line 3—3 of Fig. 1, and

Fig. 4 is a fragmentary detail sectional view of the mounting of one of the blades.

The numeral 1 designates a float of approximately rectangular shape which may be of any suitable construction. This float comprises a frame formed of a plurality of spaced rectangular frames 2 secured together and braced by the bracing beams 3. The 35 frame thus constructed is provided with a covering 4 of boards or other suitable material so as to provide a relatively large air chamber extending throughout the float. The sides 1^a of the float project downward 40 a considerable distance beyond the end portions 1^b which are raised to form an end inlet opening 1^c and an outlet opening 1^d at the ends of the float. As will be noted, these openings converge inwardly to the ends of 45 the central rectangular opening or well 5 extending through the float from the top to the bottom thereof. In operation the float is mounted so that the current flows from the inlet end toward the outlet end. In this position the opening 1^c permits the easy entry of a relatively large amount of water which, after operating upon the blades of the motor, to be later described, escapes through 50 the outlet 1^d.

55 Near each end of the well 5, at each side

thereof, is secured a post or standard 6, the standards at each end being in horizontal alinement. Each pair of standards supports, near the upper ends thereof, a rotatably mounted transverse shaft 7. A pulley 8 is 60 keyed on one end of this shaft and is operatively connected by a cord 9 to a similar pulley 10 keyed on a stub shaft 11 rotatably mounted on one of the standards 6 on the outer end of which is keyed a hand wheel 65 12. A pinion 13 is keyed on the shaft 7, near each end thereof, adjacent the support 6. By rotating the hand wheel 12, the pinions 13 may be rotated in either direction desired.

The pinions 13 mesh with rack bars 14 70 which are secured at the ends of an approximately V-shaped frame 15 mounted within the well 5.

The rack bars are held securely in spaced relation by brace rods 14^a secured to the bars 75 near their upper ends and extending longitudinally of the frame 15.

This frame is composed of spaced horizontal top bars 16, central downwardly projecting bars 17 secured at their upper ends 80 in the bars 16, and lower upwardly and outwardly inclined brace rods 18 secured at their lower ends to the bars 17 and at their upper ends to the outer ends of the top bars 16. This provides a relatively light 85 and very strong and rigid structure. The outer ends of the brace rods 18 and the top bars 16 are also firmly secured in the rack bars 14, near the lower ends thereof. Each rack bar is provided, near its lower end, with 90 a bearing sleeve 19 rigidly secured thereto. These sleeves rotatably support a transverse shaft 20 at each end of the frame, and a similar shaft 21 is mounted in the downwardly extending bars 17 in a plane below 95 the plane containing the axes of the shafts 20. It will be evident that, by rotating the hand wheels 12, the frame may be adjusted vertically as desired.

A sprocket wheel 22 is keyed on each 100 shaft 20, near each end thereof. A similar pair of sprocket wheels 23 is keyed on the shaft 21. These wheels are in the same vertical plane and are adapted to receive a sprocket chain 24 passed about the same. 105 There are two of these chains mounted in spaced relation in the vertically adjustable frame. Between the chains 24 are mounted a plurality of equally spaced transverse rods 25. Each of these rods is passed loosely 110

through an eye 26 formed integral with and at the approximate center of, a vane or blade 27. The outer end of this blade is provided with an integral eye 28 which receives an eye 29 at the upper end of an inclined brace rod 30, the lower end of which is pivotally secured, as at 31, to the inner face of one of the links of the chain 24. The blades 27 are mounted at right angles 10 to the chains and are normally maintained in this position by the brace rods 30. When the chain passes about one of the sprocket wheels the distance between the rod 25 and the pivotal point 31 will be slightly decreased so that the blade will rock about the rod. The pivotal mounting of the blade and the brace rod, and the loose connection between the outer end of the brace rod and the upper end of the blade, permit this rocking 15 movement during the travel of a blade about one of the sprocket wheels, while normally holding the blade at right angles to the chains, as above stated.

Due to the fact that the sprocket wheels 25 23 are somewhat lower than the sprocket wheels 22, the blades, during the first half of the lower part of their travel, will travel downward at an inclination so that they will be presented to the water at a downward and 30 outward slant. Due to this slant or inclination of the blades, the water obtains a firm grip upon the same so as to move them in the direction of flow of the operating fluid. During the latter half of their lower travel, the blades are at an upward and inward inclination, so that the water exerts a lifting or buoyant effect upon them, thus preventing the blades from engaging the water at such an angle as to present an appreciable 35 resistance to their movement through the same. By dividing the lower run of travel of the blades into two parts, as described, I am enabled to obtain a maximum amount of power from a given flow of water, and the 40 resistance of the blades to their movement through the water is reduced to a minimum.

By raising or lowering the frame which supports the belt which carries the blades

formed by the chains 24, operation of the motor may be controlled at will. 50

One of the end shafts 20 of the chain carrying frame is extended and a pulley 32 is keyed on the outer end thereof. This pulley is in alinement with an opening 33 through the top of the float 1. By this means the motor may be connected by a belt, or the like, to the machinery which it is desired to operate therefrom.

It will be evident that certain changes can be made in the construction and arrangement of the different parts of my invention without departing from the field and scope of the same, and I intend to include all such variations, as fall within the scope of the appended claim, in this application, in which a preferred form only of my invention is disclosed.

What I claim, is:—

In a water motor, a frame, pairs of spaced sprocket wheels rotatably mounted at the center and each end of the frame in triangular arrangement, the sprocket wheels at the center being in a plane lower than those at the ends of the frame, a pair of chains passed about the sprocket wheels, a plurality of blades rockably mounted at their centers between the chains and disposed at right angles thereto, each of said blades being provided at its center with an integral eye extending the full length thereof, a rod 75 inserted through said eye and secured between the chains so as to rockably support the blade and brace rods pivotally secured at their lower ends to the outer end of said blades and pivotally secured at their inner 80 ends to said chains said rods acting to hold the blades at right angles to the chains, and permitting rocking movement thereof when passing about a sprocket wheel.

In testimony whereof I affix my signature 90 in presence of two witnesses.

ERICK G. ANDERSON.
